UNITED STATES PATENT OFFICE

JOSEPH A. CAPELLE, OF GLADSTONE, VIRGINIA

RAILROAD RAIL

Application filed October 4, 1930. Serial No. 486,488.

Rails for railroads now commonly used are a length that is a single or unitary piece that comprises ball, web and base. When such a rail must be replaced on account of wear, the 5 whole unit must be scrapped and replaced although it may be only the ball is worn to the point that the rail must be discarded. This means great loss in mere cost of metal. It also means serious labor cost because of 10 the necessity of removing spikes from ties and driving spikes to secure the replaced rail. It means damage to the ties in withdrawing spikes and there is the cost of plugging the spike holes when the new rail is 15 spiked, and, of course, the labor of respiking is an important item of cost. Again the cost is added to by the necessity of regaging the rails and renewing rail joints and tie plates. Other objections to the present rail construction 20 on account of the joints where the rails come end to end are want of smoothness from the vertical vibrations at the rail ends, the considerable expense of retamping such ends from time to time to level up the ends, the 25 danger of breakage of the rails from the vertical vibrations of the ends at the joints, wear and tear of the rolling stock because of the undue strains thereon in consequence of loose conditions at the joints and the possibility of 30 derailments because of bad conditions at the rail joints.

The object of my invention is to provide a rail construction by which, in what I consider the best embodiment of my invention at the present time, all of the objections just mentioned will be obviated or overcome and practical benefits or advantages secured which do not characterize the ordinary rail construction.

The basic or underlying idea of my invention is the construction of a rail of two longitudinal parts, one constituting the ball or wheel-engaged member and the other constituting the base or tie-engaging member, each of these members having a part which together make up the rail web, the ball member being removable and replaceable from time to time as wear may require, so that only 45 after long periods of time or at all the base

member need be removed and hence is permanently a part of the road bed.

My invention consists in whatever is described by or is included within the terms or scope of the appended claims.

In the accompanying drawings:—

Fig. 1 is a perspective view of a rail embodying my invention;

Fig. 2 is a cross section thereof.

In the embodiment of my invention shown in the drawings, the cross-section of my two-part rail is that of the standard rail and includes the ball, 10, with a single central web, 11, the ball and head being thus T-shaped in cross section and a base or flange, 12, with a central web, 13, that reaches to the underside of the ball and has a central slot, 14, to receive the ball web or stem, 11, and engage it on opposite sides. A close or snug fit of the ball stem or web in the slot, 14, of the base is desirable to avoid any play or lost motion which would be objectionable because of noise that might result but which would be more objectionable as impairing the strength and rigidity of the rail structure. To secure that snug or tight fit the ball web may be made tapering from top to bottom either partially or wholly and the walls of the slot correspondingly formed so that when the ball web is inserted in the slot to the full extent there will be close contact of the side surfaces of ball web and slot walls. The abutting side surfaces may be straight or plane or as shown in the drawings they may be slightly curved from the underside of the ball downward. If desired, the width of the slot from side to side may be slightly less than the thickness of the web, 11, from side to side so as to assure the desired snug or close fit, there being enough spring or elasticity in the slotted web of the base member to allow the thrusting of the ball web into the slot.

Preferably to add to the strength and rigidity of the two part or composite rail, the upper ends, 15, of the slot walls are thickened and extend laterally so that their upper faces are of considerable extent and bear against the outwardly and upwardly inclined under face of each side of the ball, 10. By reason of this construction, it will be evi- 100

dent that my rail is able to resist the stresses from the lateral or side-wise thrust of the car wheel flanges on the ball and thus a strong and rigid construction is provided. The outward and upward inclination of the bearing faces offers resistance to such lateral thrust.

Preferably the bottom edge of the ball web contacts with the bottom of the slot so that bearing contact is provided at that point as well as on the underside of the ball. The ball and base members constituting the rail are assembled so as to break joints and at each side of the joints are transverse bolts passing through the web portions of the two members and at other points along the length of the rail as may be desired. No joint plates need be provided or employed unless it is preferred because the break joint construction makes that usually unnecessary. As the breaking of the joints eliminates a joint extending from top to bottom of the rail which exists with the ordinary one-piece rail construction, it will be seen that my rail eliminates the condition hereinbefore pointed out which results in lowering of the rail ends at the joints and the serious consequences to rails, rolling stock and passengers which come from the joint with the one piece rail construction.

An important feature of my invention is the provision of the slot in the base member and the single web on the ball member. This means the minimum of metal for the ball member with the important advantages of saving of cost by saving of metal so that when the ball member is scrapped because of wear there is the minimum loss of metal and the minimum quantity of metal for the new or replacement ball member; and labor and cost of handling in transportation and installation is saved. If for instance the construction should be reversed so that the slotted web is a part of the ball, then the ball would carry or have the weight of an additional web member which in a rail of standard thirty-nine foot length would obviously be an important matter.

The one-piece rail construction requires a hard steel to enable the rail ball to resist wear. That means that the entire rail must be made of the same hard steel and that steel does not have the toughness and elasticity which are a safeguard against fracture or breakage. By my invention the ball can be made of steel suitable to resist wear and the base made of a steel of different texture which will provide toughness and elasticity that are important to withstand breakage from the stresses that fall upon the rail in use.

It will be evident that a rail having the characteristics of construction shown in drawings and described herein at length will obviate or be free from the serious objections hereinbefore pointed out to the one-piece rail construction and will have advan-

tages or benefits which will be appreciated by those skilled in the art due to the special construction of my rail.

When a ball is worn on one side, it need not be discarded but by reversing it to place its unworn side towards the wheel flange, its use can be continued.

A rail having the characteristics of my invention is available for use in all railroad constructions whether for steam or electric roads, and I do not confine myself to rails for any particular use.

What I claim is:

1. A rail having a ball and a base with outwardly extending tie-engaging flanges at the base comprising separately united longitudinal members, the ball having on its underside a single central web member and the base a web member with a vertical slot in which the ball web member fits completely filling the space between the slot side walls, the side walls of the slot being thickened laterally adjacent and contacting with the underside of the ball; the contacting surfaces inclining outward and upward the thickening being gradually upward from the outer side.

2. A rail as in claim 1 in which the portion of the web covered by the thickened portions of the side walls is thicker than the portion of the web below the same.

3. A rail as in claim 1 in which the thickened portion of the side walls of the slot extend a substantial distance downward over the web member, and the outer surfaces of said side walls being uninterrupted from top to bottom.

In testimony whereof I hereunto affix my signature.

JOSEPH A. CAPELLE.
